DELCO-REMY CORPORATION, OF DAYTON, OHIO, A CORPORATION OF DELAWARE.

APPARATUS FOR PRESS-FITTING COMMUTATORS UPON ARMATURE SHAFTS.

Application filed August 21, 1926. Serial No. 130,738.

This invention relates to apparatus for assembling tubular bodies upon shafts and particularly for assembling a commutator having a tubular hub upon the shaft having a 5 commutator receiving portion over which the commutator is press-fitted.

It is among the objects of the present invention to provide apparatus for facilitating the assembling operation referred to in 10 order that the cost of this part of the manufacture of a dynamo electric machine may be reduced.

Further objects and advantages of the 15 present invention will be apparent from the following description, reference being had to the accompanying drawings, wherein a preferred form of embodiment of the present invention is clearly shown.

In the drawings: 20 Fig. 1 is a fragmentary view in longitudinal section of apparatus for assembling a shaft and a commutator.

Fig. 2 is a composite sectional view on the line 2—2 of Fig. 1.

25 The shaft 20 to which the present invention is particularly adapted is one having a commutator receiving portion 21 adjacent which is a portion 22 of smaller diameter which may provide one of the journals of 30 the shaft. The shaft 20 carries a slotted armature core 23 carrying a plurality of hairpin bar conductors 24, the ends of which are arranged in concentric circular rows. The bar ends in the outer row are designated by numeral 25 and those in the inner row by the numeral 26. Thus the conductor bar ends are arranged in groups of two ends each, namely the ends 25 and 26 which extend substantially radially with respect to 40 the center of the core. Each group of two ends is to be attached to a segment of a commutator which will now be described.

The commutator to which the present invention is particularly adapted is designated 45 in its entirety by numeral 30 and includes a plurality of conducting segments 31 each located between two L-shaped conducting plates 32 having dove-tail tang portions 33 corresponding to the dove-tail tangs of the segments 31. Thus each conducting section of the commutator includes the segment 31 and portions of the L-shaped members 32. The conducting sections are spaced and insulated from each other by insulation pieces 55 shaped like the segments 31. The portions

34, 34 of the members 32 which extend from the segment 31 are called riser portions and include between them a space for receiving one of the groups of conductor bar ends 25 and 26. The conducting sections including segments 31 and plates 32 are insulatingly clamped in assembled position by V-rings 35 and a hollow rivet 36 which provides a tubular hub for the commutator and is adapted to be press-fitted over the commutator receiving portion 21 of the shaft 20.

The machine for assembling the commutator 30 upon the shaft 20 comprises a tube 40 having its lower end portion divided by a plurality of slots 41 so as to provide a plurality of flexible portions 42. The portions 42 receive the commutator hub 36 and yieldingly maintain the commutator in position upon the tube 40. The tube 40 is slidable within a tubular member 43 provided at its lower end with an annular boss 44 adapted to bear against the upper V-ring 35 of the commutator. The tubular member 43 is slidably supported by a guide 45 which is supported in any suitable manner by a base 46 indicated at 46. The central bore 47 of the tube 43 which receives the tube 40 contains a spring 48 bearing against the interior of the tube 43 and the upper end of the tube 40 in order to urge the tube 40 downwardly into the position shown in the drawing. Downward movement of the tube 40 is limited by a set screw 49 engaging the upper end 50 of a slot 51 provided in the side of the tube 40. A locating bar 52 is attached by screws 52^a to the member 43 and is adapted to occupy a space between the pair of riser members 34 in order to locate a commutator which has been placed upon the tube 40 in a definite relation to the tubular member 43. The member 43 is prevented from rotating relative to the guide 45 by a suitable key 53 attached to the guide and cooperating with the groove 54 in the member 43.

The shaft 20 and its armature core 23 are supported in a vertical position and in alignment with the tube 40 by means including a socket member 60 having a recess 61 for receiving the lower end of the shaft 20, and vertically slidable within a recess 62 in alignment with the tube 40. The block 60 is yieldingly urged upwardly by a spring 63. The armature core 23 is maintained upright and its angular relation to the base 46 and hence to the commutator 30 is determined 100

105

110

by a bracket 64 attached by screws 46 and having a half-tubular portion 66 adapted to receive the core 23. The tubular portion 66 carries a longitudinal extending rib 67 adapted to be received by one of the armature core slots and thereby locate the armature in a predetermined relation to the assembling apparatus and hence to the commutator.

10 After the shaft and armature have been located, as shown in Fig. 1, vertically below the tube 40, the tube 43 is caused to move downwardly by any suitable power operated device. As the tube 43 moves downwardly it carries with it tube 40 which temporarily supports the commutator 43. The lower end of the tube 40 is beveled at 42° so that it will readily pass over the shaft portion 22. When the lower end of the tube 40 engages the shoulder portion 42a at the junction of the portions 21 and 22, further downward movement of the tube 40 will be prevented; but the tube 43 will continue to move downwardly in order to transfer the commutator 25 from the portion 40 to the commutator receiving portion 21 of the shaft. The member 43 serves to strip the commutator from the tube 40 and also to press the commutator over the commutator receiving portion 21. 30 After this operation has been performed the member 43 is moved upwardly to the position shown in Fig. 1. The tube 40 is also moved upwardly by movement of the stripper 43 until it clears the upper end of the shaft 20 so that the work may be moved from the work holder and other work to be assembled may be placed in position.

The spring 63 cushions the shock of engagement of the commutator with the shaft 40 22, thus preventing pounding the lower end of the shaft 22 upon its support.

While the form of embodiment of the present invention as herein disclosed, constitutes a preferred form, it is to be understood that other forms might be adopted, all coming within the scope of the claims which follow.

What is claimed is as follows:

1. Apparatus for assembling a commutator having a tubular hub upon a shaft having a commutator receiving portion, comprising in combination, means for supporting the shaft; means independent of the shaft for temporarily supporting the commutator in alignment with the shaft and for locating it around the shaft and adjacent the commutator receiving portion thereof; and means for removing the commutator from the temporary supporting means and for forcing it along the commutator receiving portion of the shaft.

2. Apparatus for assembling a commutator having a tubular hub upon a shaft having a commutator receiving portion and a portion of smaller diameter than the com-

mutator receiving portion located between an end of the shaft and the commutator receiving portion, comprising in combination, a tube for receiving the commutator and adapted to receive the shaft portion of smaller diameter; means for supporting the armature shaft in alignment with the tube; means for producing relative movement between the tube and shaft so that the commutator will be located around the shaft and adjacent the commutator receiving portion thereof; and means for transferring the commutator from the tube to the commutator receiving portion of the shaft.

3. Apparatus for assembling a commutator having a tubular hub upon a shaft having a commutator receiving portion and a portion of smaller diameter than the commutator receiving portion located between an end of the shaft and the commutator receiving portion, comprising in combination, means for supporting the shaft; means independent of the shaft for temporarily supporting the commutator in alignment with the shaft and for locating it around the shaft portion of smaller diameter; and a tubular stripping member movable in alignment with the shaft and adapted to engage one end of the commutator and to remove it from the temporary holding means and to force the commutator along the commutator receiving portion of the shaft.

4. Apparatus for assembling a commutator having a tubular hub upon a shaft having a commutator receiving portion and a portion of smaller diameter than the commutator receiving portion located between an end of the shaft and the commutator receiving portion, comprising in combination, a tube for temporarily holding the commutator and adapted to receive the shaft portion of smaller diameter; a stripper supporting and guiding the tube and adapted to engage an end of the commutator; means limiting relative movement between the tube and the stripper; means for supporting the shaft in alignment with the tube; and means for producing relative movement between the shaft and the tube and stripper whereby the commutator will be located around the shaft and adjacent the commutator receiving portion thereof, and then the stripper will cause the commutator to be transferred from the tube to the commutator receiving portion of the shaft.

5. Apparatus for assembling a commutator having a tubular hub upon a shaft having a commutator receiving portion and a portion of smaller diameter than the commutator receiving portion located between an end of the shaft and the commutator receiving portion, comprising in combination, a tube for temporarily holding the commutator and adapted to receive the shaft portion of smaller diameter; a tubular stripper

supporting and guiding said commutator supporting tube and adapted to engage an end of the commutator; a spring within the stripper for urging the tube outwardly from the stripper; means for limiting the outward movement of said tube relative to the stripper; means for supporting the shaft in alignment with the tube; and means for producing relative movement between the shaft and the tube and stripper whereby the commu-

tator will be located around the shaft and adjacent the commutator receiving portion thereof, and then the stripper will cause the commutator to be transferred from the tube to the commutator receiving portion of the shaft.

In testimony whereof I hereto affix my signature.

LORA E. POOLE.
